UNITED STATES PATENT OFFICE.

DAVID J. SEAMAN, OF SOUTH BEND, INDIANA.

DESIGN FOR FABRIC.

SPECIFICATION forming part of Design No. 34,426, dated April 23, 1901.

Application filed March 27, 1901. Serial No. 53,150. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, forming a part hereof.

10 This design relates to the ornamentation of cotton, silk, woolen, paper, celluloid, and other fabrics.

In the drawing I have shown a plan view of my design.

15 The leading feature of the design is the representation of festoons of holly leaves and berries running along or upon the surface of the fabric with bunches or sprays of holly

leaves and berries depending from the points or junctions of the festoons. The leaves A 20 are interspersed with the berries B, and stems C appear at the ends of the festoons and disappear behind stars D. Sprays or bunches of holly-leaves E, interspersed with berries F, depend from the junctions of the festoons, 25 the stems G of said sprays also disappearing behind the stars.

What I claim is—

The design for a fabric described and shown.

In testimony whereof I have signed this 30 specification in the presence of two attesting witnesses.

DAVID J. SEAMAN.

Witnesses:

F. J. LEWIS MEYER,
F. M. DAVIS.
